UNITED STATES PATENT OFFICE.

GEORGE P. REINTJES, OF KANSAS CITY, MISSOURI.

WALL CONSTRUCTION.

Application filed December 7, 1925. Serial No. 73,700.

This invention relates to wall construction, and more especially to walls for furnaces and the like, subjected to high degrees of heat, and my object is to produce a wall from which at relatively small expense and in a short time, a burned section can be removed and replaced by a new section without affecting the strength or solidity of the unburned section. Another object is to produce a wall construction in which provision is made for expansion vertically and longitudinally.

With these general objects in view the invention consists in certain novel and useful features of construction and organization of parts as hereinafter described and claimed; and in order that it may be fully understood, reference is to be had to the accompanying drawings, in which:—

Figure 1 is a fragmental perspective of a double wall embodying the invention.

Figure 2 is a vertical section taken on the line II—II of Figure 1.

Figure 3 is a plan view of a section of the wall at any level where brick work only occurs.

Figure 4 is a detail perspective view of one of the cover tiles of the wall.

Figure 5 is a detail perspective view of one of the permanent or outer wall-member tiles.

Figure 6 is a detail perspective view of one of the inner wall-member tiles for interlocking engagement with an outer wall-member tile of the same horizontal course.

Figure 7 is an enlarged fragmental plan view showing the interlocking of tiles of the same course of the two wall members, and also how an interlocking tile of the inner wall member can be placed in or removed without disturbing the adjacent corresponding tile or the adjacent outer wall-member tile.

Figure 8 is a fragmental perspective view of the preferred construction of the wall at a level where it is not subject to the action of flame and hence where replacements of tile are not contemplated.

Figure 9 is an enlarged plan view of the construction shown by Figure 8.

Figure 10 is a detail perspective view of an irremovable tile designed for use in the construction shown by Figures 8 and 9 as a

substitute for a pair of removable tiles as shown in Figure 7.

In the said drawings, a wall structure is shown composed of an inner member 1 and an outer member 2 generally spaced apart longitudinally at 3 but interlocked together at predetermined levels without interfering with expansion or contraction.

The outer member, as not subjected to contact with flame, is erected of suitably arranged ordinary brick 4 or the like, and at suitably spaced levels there are single courses of the brick and tiles 5, which latter are provided at their inner ends with laterally-projecting rounded lugs or ears 6. Preferably the distance between adjacent tiles 5, of the same course, equals the length of two bricks.

The inner member is erected of suitably arranged refractory brick or the like 7, and pairs of tiles 8, placed at the same levels as tiles 5, and the pairs of tiles 8, project outward into the outer member and substantially fill the spaces between adjacent tiles 5 for the width of the inner vertical course of the brick 4, each tile 8 having a recess 9 in its outer side edge loosely receiving the proximate lug or ear 6 of the adjacent tile 5, the interlocking arrangement of the ears and recesses being such that independent endwise movement inwardly or outwardly of either the tiles 5 or the tiles 8 is prevented. Tiles 8 engaging the same tile 5, are separated by pairs of interposed bricks 7 of the inner member, and such bricks in the same course as the said tiles 8, hold the latter in sidewise abutting relation at the inner face of the inner member of the wall, but from the plane of such face the adjacent side edges of the pairs of tiles diverge outward relatively to provide interposed V-shaped spaces 10, the parts being so proportioned that it is possible, when a pair of bricks in a particular course are removed, to pivotally swing either adjacent tile 8 around the engaging lug or ear 6 to permit the tile to be withdrawn without interference from the companion tile 8, as shown by Figure 7.

The removed tile or tiles can be replaced or new one substituted by a reversal of the manipulation described, and the method of operation described can be followed at any intermediate point and level on the inner face

of the wall, as all preliminary work required is the chiseling out of such pair of bricks between the two tiles where the removal is to be effected, it being understood of course, that the burned or imperfect brick 7 in the vicinity of the tile or tiles to be removed, will also be replaced when the replacement of the tiles occurs. As an illustration, if it be assumed that the wall needs repair within the ellipse traced on Figure 1, all the brick 7 and the two tiles touched by or within the elliptical figure, may be readily removed, the brick in any desired manner and the tile as explained, and a repair 15 made without affecting the remainder of the inner members of the wall or the outer member spaced from but in interlocking relation therewith.

The tiles 5 and 8, and the bricks of the inner and outer walls inward of tiles 5 and outward of tiles 8, respectively, are slightly spaced apart for facilitation of vertical and longitudinal expansion of the inner wall member. It has been found that of the longitudinal expansion of such member comparatively little occurs at the inner face, and for this reason it is feasible to abut the tiles 8 sidewise at their inner extremities and against the interposed pairs of brick 7. To accommodate variable vertical expansion at different levels, a course of cover tiles 11 for each course of interlocking tiles, is provided. The cover tiles are preferably of such width that every fourth one overlies the outer ends of a pair of adjacent tiles 8, the two intermediate cover tiles jointly overlying one of the tiles 5 and the brick work 4 flanking such tile.

The cover tiles, like the tiles 5, are permanent, being cemented or otherwise secured to and as a part of the outer wall member. They may be of step form (see Figure 4) to provide spaces between them and the overlapped tiles 8, but the cheaper and therefore preferred method of providing for the spacing of the inner or overlapping ends of the cover tile from the tile 8 is to provide deep courses of mortar or cement 12 for the cover tiles, as by so doing the spaces can be provided by using conventional or stock tile of uniform thickness somewhat less than that of the bricks, it being also preferred that the cover tiles shall project across the space 3 to subdivide the same as to depth, in to as many divisions as there are courses of cover tile. This subdivision of the space 3 is desirable, as when two high walls 1 and 2 are provided in proximity to each other, it is desirable to fill the space 3 with crushed fire brick or the like, and if subdivided as explained, the filling will not pack materially and hence will not expand laterally enough to warp the wall members, as might occur if the filling was a solid mass from the bottom to the top of the wall. To facili-

tate longitudinal expansion of the inner wall in the brick courses between the courses containing tiles 8, some bricks at suitable intervals, will be of tapered form to provide the outwardly-flaring spaces 7.

By reference to Figures 8 and 9, it will be seen that the construction described is followed except in the fact that in lieu of each pair of removable tiles 8, a single tile 14 is employed for interlocking engagement with the adjacent tiles 5, it being also noted the last-named tiles are disposed only the length of a brick apart as contrasted with the same tiles in the preceding figures, where they are two bricks lengths apart. This difference is immaterial in principle and is made only to avoid the necessity of making the tiles 14 of undesirable width and weight.

It will also be noted that the tiles 14 are permanent tiles in the sense that they cannot be removed by pivotal adjustment should adjacent bricks 7 be chiseled out or otherwise removed. It is anticipated that certain parts of the inner wall,—the upper for example—will never be subjected to such continuous contact with flame as to be in need of replacement, and at such points it may be desirable to employ tiles of the character or type disclosed by Figures 8 and 9, as with such tiles longitudinal and vertical expansion can be accommodated as conveniently as where the removable tiles 8 are employed.

From the above description it will be apparent that I have produced a wall embodying the features of construction and arrangement set forth as desirable, and it is to be understood that I reserve the right to make such changes as properly fall within the spirit and scope of the appended claims.

I claim:

1. A wall composed of superposed courses and comprising an inner refractory member and an outer member, each member including brickwork and one or more horizontal tile courses at desired levels, and each tile course of one member being in the same horizontal plane as a tile course of the other member, the tiles of the outer wall member being spaced apart, and the tiles of the inner wall member being arranged in juxtaposed pairs spaced apart by the outer wall tiles and projecting outwardly into the outer wall, and each tile of each of the said pairs being interlocked with one of the outer wall tiles as regards independent movement transversely of the wall.

2. A wall composed of superposed courses and comprising an inner refractory member and an outer member, each member including brickwork and one or more horizontal tile courses at desired levels, and each tile course of one member being in the same horizontal plane as a tile course of the other member, the tiles of the outer wall member

- being spaced apart, and the tiles of the inner wall member being arranged in juxtaposed pairs spaced apart by the outer wall tiles and projecting outwardly into the outer wall; each tile of one wall member having an outwardly projecting lug at its inner end and each of the other wall tiles having a recess in one edge near its inner end engaged by a lug of the adjacent tile of the other wall. 10
3. A wall composed of superposed courses and comprising an inner refractory member and an outer member, each member including brickwork and one or more horizontal tile courses at desired levels, and each tile course of one member being in the same horizontal plane as a tile course of the other member, the tiles of the outer wall member being spaced apart, and the tiles of the inner wall member being arranged in juxtaposed pairs spaced apart by the outer wall tiles and projecting outwardly into the outer wall; the tiles of the inner wall member having side recesses and adjacent tiles of the other member having rounded side lugs pivotally engaging such recesses, the adjacent edges of the pairs of tiles of the inner wall member extending in an outwardly diverging direction. 15
4. A wall composed of superposed courses and comprising an inner refractory member and an outer member, each member including brick work and one or more horizontal tile courses at desired levels, and each tile course of one member being in the same horizontal plane as a tile course of the other member, tiles of the same horizontal course of one member having side recesses and adjacent tiles of the other member of the same horizontal course, having side lugs engaging such recesses, one of the tiles of the courses of each member being transversely aligned with brick work of the other member. 20
5. A wall composed of superposed courses and comprising an inner refractory member and an outer member, the outer member comprising courses of brickwork and courses of both tile and brickwork, the tiles of each course extending inwardly to the inner face of the first-named brickwork courses and spaced apart at regular intervals, and the brickwork of such courses being interposed between the tiles and terminating short of the inner face of the latter, the inner member comprising courses of brickwork and courses of both tile and brickwork, the tiles of the inner wall member being arranged in pairs and projecting outwardly into the outer wall member opposite the brickwork of said last-named member in the same course, and interlocked at the side edges with the tiles of the outer wall member at the inner ends of said tile; and courses of cover tiles superimposed directly upon the combined tile and brickwork courses of the outer wall member and extending inward to abutting relation with the outer ends of the courses of brickwork immediately superimposed on the tile courses of the inner wall member and overlapping at their inner ends and spaced vertically from the ends of the tiles of the inner wall member where they project into the outer wall member. 25
6. A wall composed of superposed courses and comprising an inner refractory member and an outer member, the outer member comprising courses of brickwork and courses of both tile and brickwork, the tiles of each course extending inwardly to the inner face of the first-named brickwork courses and spaced apart at regular intervals, and the brickwork of such courses being interposed between the tiles and terminating short of the inner face of the latter, the inner member comprising courses of brickwork and courses of both tile and brickwork, the tiles of the inner wall member being arranged in pairs and projecting outwardly into the outer wall member opposite the brickwork of said last-named member in the same course, and interlocked at the side edges with the tiles of the outer wall member at the inner ends of said tile; and courses of cover tiles superimposed directly upon the combined tile and brickwork courses of the outer wall member and extending inward to abutting relation with the outer ends of the courses of brickwork immediately superimposed on the tile courses of the inner wall member and overlapping at their inner ends and spaced vertically from the ends of the tiles of the inner wall member where they project into the outer wall member. 30
7. A wall composed of superposed courses and comprising an inner refractory member composed of brickwork and tile, and an outer member also composed of brickwork and tile, the two members being spaced apart to accommodate lateral expansion of the walls, the outer wall member having its tiles spaced apart, and provided at their inner ends with outwardly projecting side lugs, and the inner wall member having tiles in the same courses as the tiles of the outer wall member and arranged in pairs projecting outwardly into the outer wall member between the tiles and the latter, the adjacent side edges of the pairs of tiles extending divergingly outward and their remote side edges interlocked with the side edges of the outer wall tiles between which said pairs of tiles project; adjacent bricks at suitable intervals, of each brickwork course of the inner wall member, extending at their abutting side edges divergingly outward to cooperate with the correspondingly diverging edges of the pairs of tiles in accommodating longitudinal expansion of the inner wall member. 35

4
8. A wall composed of an inner member of refractory material, and an outer member spaced laterally apart to accommodate lateral expansion of the members, each member being composed of superposed horizontal courses of masonry, and one of the walls having one or more horizontal courses of

cover tiles bridging the space between the members, and each cover course overhanging and spaced from the next lower course of the ¹⁰ other member.

In witness whereof I hereunto affix my signature.

GEORGE P. REINTJES.
